CLAIM

The ornamental design for a line angle indicator, as shown.

DESCRIPTION

FIG. 1 is an isometric view of the line angle indicator of this design showing characteristic features of the unique design of the invention.

FIG. 2 is a front view of the line angle indicator of this design.

FIG. 3 is a rear view of the line angle indicator of this design; and,

FIG. 4 is side view of the line angle indicator of this design. The two screw fasteners have been eliminated for ease of illustration in FIGS. 2-4.
